UNITED STATES PATENT OFFICE.

JAMES S. THOMPSON, OF PELHAM, NEW YORK, ASSIGNOR TO THE AMERICAN BRAKE SHOE AND FOUNDRY COMPANY, OF WILMINGTON, DELAWARE, A CORPORATION OF DELAWARE.

BRAKE SHOE.

1,402,116.

Specification of Letters Patent.

Patented Jan. 3, 1922.

Application filed December 17, 1919. Serial No. 345,532.

To all whom it may concern:

Be it known that I, JAMES S. THOMPSON, a citizen of the United States, residing at Pelham, in the county of Westchester and State of New York, have invented certain new and useful Improvements in Brake Shoes, of which the following is a specification.

This invention relates to improvements in brake shoes, and more particularly to that type in which the body metal is cast upon a plurality of strips, or a bundle, of expanded metal, or wire mesh, or other binding, bonding or reinforcing reticulated metal.

Very satisfactory results have been obtained in the past by arranging strips of expanded metal in layers, or in a bundle, one upon the other and parallel with the wearing face of the shoe whereby a wearing face will always be provided of a finely divided and composite character.

I have discovered that even better results may be obtained by arranging the expanded metal or other reticulated metal strips on edge to the wearing face, instead of flatwise thereto, and spaced apart between the sides of the shoe.

The object of the invention is to improve this type of brake shoes by arranging the expanded metal or other reticulated metal strips therein in a novel manner which simplifies the construction, produces a stronger and stiffer shoe, and at the same time preserves all the desirable features of a shoe in which the ductile metal is distributed throughout the cast metal body to provide a composite wearing face in which the constituent parts constantly change in area and position.

My present invention may be embodied in different ways and in different kinds and shapes of brake shoes, and in the accompanying drawings I have illustrated some of these embodiments. Referring to the drawings—

Fig. 1 is a side elevation partly in section of a simple form of car shoe having expanded metal strips embedded therein in an inclined position on edge to the wearing face of the shoe.

Fig. 2 is a transverse sectional view on the line 2—2 of Fig. 1.

Fig. 3 is a view similar to Fig. 1 showing the expanded metal strips in staggered relation.

Fig. 4 is a transverse sectional view on the line 4—4 of Fig. 3.

Fig. 5 shows a flanged brake shoe having the expanded metal strips with insert sections or blocks cast thereon and embedded in the shoe.

Fig. 6 is a transverse sectional view on the line 6—6 of Fig. 5.

Fig. 7 is a view similar to Fig. 5 showing the expanded metal strips in staggered relation.

Fig. 8 is a transverse sectional view on the line 8—8 of Fig. 7.

Figs. 9 to 12 are sectional views corresponding to Figs. 2, 4, 6 and 8 but showing the strips upright instead of inclined.

Fig. 13 is a view similar to Fig. 5 with wire mesh strips substituted for the expanded metal strips.

Fig. 14 is a cross-sectional view on the line 14—14 of Fig. 13.

Fig. 15 is a view similar to Fig. 13 with the wire mesh strips arranged in staggered relation.

Fig. 16 is a cross-sectional view on the line 16—16 of Fig. 15.

Figs. 17 and 18 are sectional views corresponding to Figs 14 and 16 but showing the strips upright instead of inclined.

Referring to the drawings, the body 16 is 85 preferably provided with a suitable reinforcing and strengthening ductile metal back 17 which may be made in any of the variety of different ways well known in the art. A plurality of reticulated metal strips 90

are arranged on edge to the wearing face of the shoe and spaced apart between the sides of the shoe. These strips may consist of commercial expanded metal 18, as shown in Figs. 1 to 12 inclusive, or they may consist of commercial wire mesh 19, as shown in Figs. 13 to 18 inclusive, or they may consist of any other suitable reinforcing, reticulated metal which will produce the same, or substantially the same, results. 95

The strips may be arranged in the body of the shoe with their interstices registering as shown in Figs. 15 and 12, or they may be arranged in staggered relation as shown in Figs. 3, 7 and 15. The strips are preferably curved on an arc corresponding substantially with the curvature of the wearing face of the shoe, and they may be spot-welded to the reinforcing back where they contact therewith, if desired. 105

Insert sections or blocks 20 of any desired metal may be cast on the strips, in suitable shapes and at such intervals as may be required, so that the sections or blocks will be rigidly interlocked with the strips and the strips will be held in spaced relation by the sections or blocks. The interlocked sections or blocks and strips form an insert which is placed in a mold 10 with the reinforcing back and the body metal is then cast thereon to form a shoe of composite character in which all the parts are so interlocked that the danger of parts of the shoe falling away in case of fracture will be practically, if not entirely, eliminated.

The reticulated metal strips of expanded metal, wire mesh, or other material are arranged on edge to the wearing face of the shoe in an inclined or tilted position as shown in Figs. 2, 4, 6, 8, 14 and 16 or in an upright position substantially perpendicular to the wearing face as shown in Figs. 9, 10, 11, 12, 17 and 18. When the strips 20 are inclined or tilted, the position of the parts thereof exposed on the wearing face of the shoe will change as the shoe wears down thereby avoiding any chances there may be of the strips cutting or scoring the 30 wheel.

I have shown the reticulated strips regularly spaced between the sides of the shoe, and, while this is now considered to be the most desirable embodiment of the invention, 35 I may vary the arrangement and may position the strips close together in the form of a bundle if it shall prove to be a desirable construction. The strips may be held in their proper relative position for casting 40 the body metal by any suitable means well known in foundry practice, but when insert sections or blocks are employed they will hold the strips in position. The use of insert sections or blocks in various sizes and 45 shapes and of different materials has been well known in the brake shoe art for many years, and it will not be necessary to enter into a discussion of the scope of the invention with relation thereto except to say 50 that I reserve the right to use any insert sections or blocks cast on any suitable reticulated metal strips that may come within the scope of the following claims.

I claim:

55 1. A brake shoe comprising a reinforcing back, a plurality of reticulated metal strips, and a body cast on the back and strips, said strips being spaced apart at intervals between the sides of the shoe and arranged on 60 edge to the wearing face of the shoe.

2. A brake shoe comprising a body, and a plurality of reticulated metal strips embedded in the body in an inclined position on edge to the wearing face of the shoe.

65 3. A brake shoe comprising a body, and a

plurality of reticulated metal strips spaced apart at intervals and embedded in the body in an inclined position on edge to the wearing face of the shoe.

4. A brake shoe comprising a reinforcing 70 back, a plurality of reticulated metal strips, sections or blocks cast on the strips at spaced intervals, and a body cast on the back and strips and sections or blocks, said strips being spaced apart at intervals between the 75 sides of the shoe and arranged on edge to the wearing face of the shoe.

5. A brake shoe comprising a reinforcing back, a plurality of reticulated metal strips, sections or blocks cast on the strips and extending transversely of the strips at spaced 80 intervals between the ends of the strips, and a body cast on the back and strips and sections or blocks, said strips being spaced apart at intervals between the sides of the 85 shoe and arranged on edge to the wearing face of the shoe.

6. A brake shoe comprising a body, a plurality of reticulated metal strips embedded in the body in an inclined position on edge 90 to the wearing face of the shoe, and insert sections or blocks cast on the strips at spaced intervals and embedded therewith in the body of the shoe.

7. A brake shoe comprising a body, and a 95 plurality of expanded metal strips embedded in the body in an inclined position on edge to the wearing face of the shoe.

8. A brake shoe comprising a body, and a plurality of expanded metal strips embedded in the body at spaced intervals transversely of the shoe, said strips being correspondingly inclined on edge to the wearing 100 face of the shoe.

9. A brake shoe comprising a reinforcing 10 back, a plurality of reticulated metal strips arranged in an inclined position on edge to said back, and a body cast on the back and strips.

10. A brake shoe comprising a reinforcing 11 back, a plurality of reticulated metal strips, and a body cast on the back and strips, said strips being spaced apart at intervals and arranged in an inclined position in the shoe on edge to the back and to the wearing face 11 of the shoe.

11. A brake shoe comprising a reinforcing back, a plurality of reticulated metal strips arranged side by side and spaced apart at intervals with the openings in the several 12 strips in substantial registration, and a body cast on the back and strips, said strips being arranged in an inclined position on edge to the back and to the wearing face of the shoe.

12. A brake shoe comprising a reinforcing 12 back, a plurality of reticulated metal strips arranged on edge to said back and secured directly thereto, and a body cast on the back and strips.

13. A brake shoe comprising a reinforcing 13

back, a plurality of reticulated metal strips arranged on edge to the back and spot-welded thereto, and a body cast on the back and strips.

14. A brake shoe comprising a reinforcing back, a plurality of expanded metal strips arranged on edge to the back and secured directly thereto, and a body cast on the back and strips.

15. A brake shoe comprising a reinforcing back, a plurality of reticulated metal strips spaced apart in an inclined position on edge to the back and secured thereto, and a body cast on the back and strips.

16. A brake shoe comprising a reinforcing back, a plurality of reticulated metal strips secured on edge to the back, a plurality of insert sections or blocks cast on said strips,

and a body cast on the back, strips and sections or blocks.

17. A brake shoe comprising a reinforcing back, a plurality of reticulated metal strips spaced apart at intervals on edge to the back and secured thereto, a plurality of insert sections or blocks cast on said strips, and a body cast on the back, strips and sections or blocks.

18. A brake shoe comprising a reinforcing back, a plurality of reticulated metal strips secured in an inclined position on edge to the back, a plurality of insert sections or blocks cast on said strips, and a body cast on the back, strips and sections or blocks.

JAMES S. THOMPSON.
